CLAIM

The ornamental design for a display screen with epioscopy icon, as shown and described.

DESCRIPTION

FIG. 1 is a front view of a first embodiment of a display screen with epioscopy icon showing the new design; and, FIG. 2 is a front view of a second embodiment of a display screen with epioscopy icon.

The outermost rectangle illustrates a display screen. The broken lines in FIG. 2 illustrate portions of the graphical user interface that form no part of the claimed design.

1 Claim, 2 Drawing Sheets
